CLAIM

The ornamental design for a printer, as shown and described.

DESCRIPTION

FIG. 1 is an isometric view of a printer.

FIG. 2 is a view of the printer from the right side.

FIG. 3 is a view of the printer from the front side.

FIG. 4 is a view of the printer from the left side.

FIG. 5 is a view of the printer from the back side.

FIG. 6 is a view of the printer from the top side; and,

FIG. 7 is a view of the printer from the bottom side.

The broken lines shown in the views are included for the purpose of illustrating portions of the printer that no form no part of the claimed design.

The trademark forming part of the claimed design, in FIGS. 1, 2, and 4, is a registered trademark of Esselte IPR AB Corporation Sweden.

1 Claim, 4 Drawing Sheets
